US00D736669S

(12) United States Design Patent
Hardy et al.

(10) Patent No.: US D736,669 S
(45) Date of Patent: * Aug. 18, 2015

(54) MODEL

(71) Applicant: Design Ideas, Ltd., Springfield, IL (US)

(72) Inventors: Christopher T. Hardy, Springfield, IL (US); Ryan W. Varnum, Springfield, IL (US)

(73) Assignee: Design Ideas, Ltd., Springfield, IL (US)

() Term: 14 Years

(21) Appl. No.: 29/467,588

(22) Filed: Sep. 20, 2013

(51) LOC (10) Cl. 11-02

(52) U.S. Cl.

USPC D11/158

(58) Field of Classification Search

USPC D11/160, 131, 133, 134, 135, 157, 158, D11/184; D21/621, 627; D20/24, 25, 29, D20/30; 40/411, 418; 446/99, 375
